H. MILLER.

DEVICE FOR SECURING AND SUPPORTING DOORS.

APPLICATION FILED DEC. 28, 1920.

1,418,822.

Patented June 6, 1922.

Inventor
Henry Miller
By his Attorney
Andrew F. Miller Jr.

UNITED STATES PATENT OFFICE.

HENRY MILLER, OF NEW YORK, N. Y.

DEVICE FOR SECURING AND SUPPORTING DOORS.

1,418,822.

Specification of Letters Patent. Patented June 6, 1922.

Application filed December 28, 1920. Serial No. 433,578.

To all whom it may concern:

Be it known that I, HENRY MILLER, a citizen of the United States, and resident of borough of Bronx, in the county of Bronx and State of New York, have invented certain new and useful Improvements in Devices for Securing and Supporting Doors, of which the following is a specification.

My invention relates to improvements 10 in devices for securing and supporting doors, and the object of my invention is to provide a device by which a door or the like may be secured in its open or closed position as well as at intermediate positions. A further object of my invention 15 is to provide a device whereby a door may be supported to relieve the strain on the door, and a further object of my invention is to provide a simple and convenient door 20 lock and supporting device.

I accomplish these objects by the device illustrated in the accompanying drawings in which—

Figure 1 is a view of the device attached 25 to a door and

Figure 2 is an end view of a detail of the lock and

Figure 3 is a section on the line 3—3 in Figure 1 and Figure 4 is a view showing a detail of the door, bolt and socket with the several positions shown in dotted lines.

Similar reference characters refer to similar parts throughout the several views.

35 In a swinging door or gate there is a severe strain on the door and hinges when open or partially open, and in cases where no rest is provided on the sill, this strain is constant. This results in unsatisfactory 40 operation of the door, and causes the door to sag which interferes with its operation. A further objection to the doors at present in use is that when not locked in an open or closed position, the door is free to swing 45 frequently resulting in damage to the door and to persons and vehicles using the doorway. By means of my device these objections are entirely eliminated.

I provide upon a door 1 preferably near 50 its outer edge a box 2, which may for convenience be provided with a cover 3 secured to the box by means of screws 4 4 bolts or the like. Within the box 2 I provide a central pivot 5 upon which I mount 55 a lever 6 by means of a bolt 7 or the like. In the side of the box 2 I provide an open

slot 8 provided with a toothed rack 9 and on the under side of the lever 6 I provide a lug 10 adapted to engage the teeth 9. This lug 10 is preferably formed by bending 60 over a section of the marginal edge of the lever 6. The end section 11 of the lever 6 projects beyond the box 2 to form a handle. On the lever 6 intermediate the pivot 5 and the rack 9, I provide a vertical sliding shaft 12 which is preferably secured to the lever 6 by means of a yoke 12' and a pin 13. At a point on the lever 6 adjacent its inner end, I provide a vertical shaft 14 which may be secured to the 70 lever 6 by means of a yoke 14' and a pin 15. The shafts 12 and 14 are preferably provided with screw threaded end sections or the like whereby they may be extended to any desired length, so that in their normal 75 positions they will not extend beyond the bottom and top respectively of the door 1. Suitable collars 12² and 12³ are provided on the extended shaft 12 to bind it in sliding relation to the door, and in like 80 manner suitable collars 14² and 14³ are provided on the extended shaft 14 to bind it in sliding relation to the door.

My device being thus assembled and the shafts 12 and 14 lying within the limits of 85 the door, the door may be swung freely on its hinges. When it is desired to lock and support the door the lever 6 is depressed by means of the handle 11 which will drive the shaft 12 down upon the floor and serve 90 as a support for the door which may thus be supported in any desired position. If desired, suitable sockets 16 may be provided in the floor to receive the end of the shaft 12, at one or more positions of the door but 95 it is desirable that these sockets be of such depth as to permit the shaft 12 to raise the door and support it when seated in the socket. The door having been thus supported the lug 10 on the lever 6 is caused 100 to engage one of the teeth of the rack 9 thereby serving to finally lock the lever 6 in the desired position. The shaft 14 serves as a counter-balance weight to raise the shaft 12 and it may also be used to engage 105 a suitable socket 17 in the lintel of the doorway to lock the door.

Having thus described my invention what I claim is:

1. In a device of the character described 110 the combination of a lever adapted to be pivoted upon a door, a toothed rack adapt-

- ed to engage the lever and a shaft secured to the lever intermediate the rack and the point at which the lever is pivoted substantially as shown and described.
- 5 2. In a device of the character described the combination of a plate adapted to be secured to a door, a lever pivoted thereon, a toothed rack on the plate adapted to engage the lever, a shaft on the lever intermediate the pivot and the rack, and adapted to be depressed by the lever to support the door and a counter-balance weight on the end section of the lever substantially as shown and described.
- 10 15 3. In a device of the character described

the combination of a door, a box adapted to be secured to the door and having an open slot in its side, a toothed rack adjacent the slot, a lever pivoted in the box and having a section turned over to engage the rack 20 and having an end section projecting through the slot to form a handle, a plurality of shafts secured to the lever and adapted to be elevated and depressed by the swinging of the lever substantially as 25 shown and described.

Signed at New York, in the county of New York and State of New York, this 20th day of December, A. D. 1920.

HENRY MILLER.
